(57) CLAIM

The ornamental design for an infant undergarment, as shown and described.

DESCRIPTION

FIG. 1 is a perspective view of the infant undergarment shown in a position of use.

FIG. 2 is a front elevation view of the invention.

FIG. 3 is a top plan view of the invention.

FIG. 4 is a bottom plan view of the invention.

FIG. 5 is a left side view of the invention.

FIG. 6 is a right side view of the invention.

FIG. 7 is a rear elevation view of the invention; and,

FIG. 8 is a front elevation view of the invention with a lower flap of the infant undergarment in a fully open position. The broken lines in the drawings depict environmental subject matter only and form no part of the claimed design.
